RAILWAY CAR UNDERFRAME AND PROCESS
OF CONSTRUCTING SAMEHerbert H. Moss, Brooklyn, N. Y., assignor, by
mesne assignments, to Union Carbide and Car-
bon Corporation, a corporation of New York

Application October 29, 1932, Serial No. 640,163

11 Claims. (Cl. 105—418)

My invention relates to railway car underframes and particularly to the construction of the ends of the center sill for the reception of the draft gear, and to the union between the bolster and the center sill.

An object of my invention is to increase the lading carrying capacity and shock resistance of the car underframe per unit weight of the car underframe.

Another object of my invention is to utilize the end metal of a center sill having a rounded form for receiving a draft gear of rectangular form and the mounting for the draft gear.

The foregoing and other objects are attained in the car underframe illustrated in the accompanying drawing, in which:

Fig. I is an end view of a car underframe in which a portion of the striker plate is broken away.

Fig. II is a sectional view along the line II—II in Fig. I disclosing the bolster in section and a side view of one end of the center sill.

Fig. III is a sectional view on the line III—III in Fig. I disclosing the bolster in section and a top view of one end of the center sill and the bolster bottom flange.

Figs. IV and V are sectional views along the lines IV—IV and V—V, respectively, in Fig. II.

Fig. VI is a cross-sectional view of the welded joint uniting the center sill and the bolster bottom flange.

To illustrate my invention, one end and an intermediate portion of a center sill 10, the draft gear mounting, and one bolster or cross support 11 are shown in the drawing. The opposite end of the center sill and its associated parts is similar in construction to the end illustrated in the drawing. The intermediate portion 12 of the center sill extending between the bolsters may have any rounded cross-section from elliptical to round. As shown herein, the sill 10 has an intermediate portion 12 provided with a round cross-section between the bolsters 11, and end portions 14 provided with a rectangular cross-section.

Preferrably the transition zone 13 between the rounded intermediate portion 12 and the rectangular end portions 14 occurs outside of the intersection of the bolster bottom flange 15 and the center sill and on the side of the bolster 11 nearest the intermediate portion of the center sill. The sill 10 is continuous from end to end and it may be conveniently made from a single length of pipe. Seamless pipe is preferred but other similar structural steel shapes having a

rounded or curviform cross-section may be used. In such a case, each end of the tube is split along its bottom longitudinal center line for a distance equal to the required length of the draft gear opening 16 which is formed in the bottom of the center sill 10. The bottom of the sill 10 is cut along a crosswise line 17 at the inner end of the longitudinal cut for a distance equal to the width of the draft gear opening 16. The rectangular portions of metal bound by the rectangle formed by the sides of the cuts and their complementary sides are turned outwardly to form outwardly extending flanges 18 on each side of the draft gear opening 16. The longitudinal edges of the flanges 18 may be trimmed to provide a flange of 15 suitable width. The ends of the tubular sill are then pressed into a shape suitable to receive the draft gear (not shown). As shown herein, the ends 14 of the sill 10 are pressed into a rectangular form and are made rectangular inwardly beyond the draft gear opening 16 for a distance sufficient to receive the center filler casting 19 and to extend beyond the bolster bottom flange 15 so that the transition zone or portion 13 will be on the inward side of the bolster 11. In deforming the ends of the center sill, the walls are preferably stretched laterally so that the middle of the rectangular walls will lie slightly within the end projection of the round intermediate portion 12 of the sill 10. Weld metal 20 is then deposited over the transition zone 13 to reinforce it in that locality and thereby compensate for the loss in strength due to the deformation of the end of the center sill.

The center filler casting 19 may be solid as shown for convenience or if desired a lighter honeycomb or web structure may be used, and it may be secured in the center sill in any suitable manner. It is preferable to secure the casting inside of the sill by cutting longitudinal slots 21 in the walls of the sill 10 and welding the casting 19 to the walls of the sill by depositing lines of weld metal 22 in the slots 21. For additional strength two or more lines of weld metal 22 may be deposited in longitudinal slots in each top, bottom and side wall.

In order to obtain an efficient joint between the cheek plates 23 and the sides of the center sill 10, an opening is cut into the side walls 24 to receive the plates 23. The adjacent edges of the cheek plates 23 and the openings are preferably beveled and welded together by layers 25 of weld metal deposited between the beveled edges. When the cheek plates 23 are inserted in the side walls of the sill 10 and butt welded thereto, the full

- strength of the weld metal and the members of the joint is utilized. As compared to a lap welded joint the weight is decreased and progressive shear is avoided.
5. The striker castings 26 may now be welded to or fitted against each end of the center sill 10. The striker castings are braced by a gusset plate 27 welded to the castings on top of the sill.
- A bolster 11 is welded to each end portion 14 of the center sill 10. The bolster 11 comprises a diaphragm 28 provided with a central notch which fits downwardly over the center sill above the pintle center of the center filler casting 19. A pair of plates 30 adapted to serve as a bolster bottom flange, center brace plate and tie plate are welded to the bottom edge of the diaphragm 28. The inner ends 34 of the plates 30 are provided with notches 31 to receive the outwardly bent flanges 18 on each side of the draft gear opening 16. The inner ends of the plates 30 are butt welded along the edge of the outwardly bent flanges 18 and along the bottom corner 32 of the rectangular portion 14 of the sill 10. The pair of plates 30, when welded to the center sill in the manner described, form an efficient joint between the center sill 10 and the bolster 11 as the stresses are transmitted from the plates 30 to the center sill in lines lying within the plane of the plates 30, the outwardly bent flanges 18 and the bottom wall 33 of the center sill. Also, the center filler casting being inserted between the side walls of the sill at this point acts to stiffen the metal between the inner ends 34 of the plates 30.
35. A center plate 35 may be riveted to the bottom of the center sill 10 and to the inner ends 34 of the flange plates 30. The center plate 35 further increases the efficiency of the bolster 11 and the joint between the bolster and center sill.
40. While I have shown the preferred form of my invention, various changes may be made therein without departing from the scope of my invention as defined in the appended claims.
- I claim:
45. 1. A center sill comprising a unitary tubular structure having end portions of polygonal cross-section and an intermediate seamless portion of curvi-form cross-section; said intermediate portion and said end portions being formed of one continuous section of metal.
50. 2. A center sill comprising a unitary tubular structure having end portions of polygonal cross-section and an intermediate seamless portion of curvi-form cross-section; said intermediate portion and said end portions being formed of one continuous section of metal; and said end portion having integral flanges extending outwardly from each side wall thereof opposite the draft gear opening.
60. 3. A railway car underframe comprising bolsters; a center sill for supporting said bolsters; said center sill having an intermediate portion between said bolsters, and end portions extending beyond said bolsters; said intermediate portion having a tubular cross-section and said end portions having a different cross-section; transition portions integrally connecting said intermediate and end portions; and weld metal deposited on said transition portions to reinforce the same.
65. 4. A railway car underframe comprising bolsters; a center sill for supporting said bolsters; said center sill having an intermediate portion between said bolsters, and end portions extend-
- ing beyond said bolsters; said intermediate portion having a curvi-form cross-section and said end portions having a quadrangular cross-section; and transition portions extending between and integrally connected with said curvi-form cross-section and said quadrangular cross-sections.
5. A railway car underframe comprising bolsters; a center sill for supporting said bolsters; said center sill having an intermediate portion between said bolsters and end portions extending beyond said bolsters; said intermediate portion having a curvi-form cross-section and said end portions having a quadrangular cross-section; transition portions extending between and integrally connected with said respective portions of curvi-form cross-section and quadrangular cross-section; and weld metal deposited over said transition portions to reinforce the same.
10. A railway car underframe comprising a tubular center sill having an opening at the end thereof in the bottom wall of said sill for the insertion of a draft gear; outwardly bent flanges on the opposite sides of said opening; a bolster having a diaphragm provided with a notch into which the center sill is received; said diaphragm having plates extending from the opposite sides of said sill in alignment with said flanges, the inner ends of said plates being butt welded to said flanges and to the sides of said center sill.
15. A railway car underframe comprising a tubular center sill having an opening at the end thereof in the bottom wall of said sill for the insertion of a draft gear; outwardly bent flanges on the opposite sides of said opening; a center filler casting extending between the side walls of said sill and secured therein; a bolster having a diaphragm provided with a notch into which the center sill is received; a pair of plates acting as a combination center brace plate, tie plate and bolster bottom flange having their top surfaces welded to the bottom edge of said diaphragm and having their ends adjacent to said sill butt welded to said outwardly bent flanges on said sill and to the sides of said sill opposite to said center filler casting.
20. A railway car underframe comprising a tubular center sill having an opening at the end thereof in the bottom wall of said sill for the insertion of a draft gear; outwardly bent flanges on the opposite sides of said opening; a center filler casting extending between the side walls of said sill and secured therein; a bolster having a diaphragm provided with a notch into which the center sill is received; a pair of plates acting as a combination center brace plate, tie plate and bolster bottom flange having their top surfaces welded to the bottom edge of said diaphragm and having their ends adjacent to said sill butt welded to said outwardly bent flanges on said sill and to the sides of said sill opposite to said center filler casting.
25. A railway car underframe comprising a tubular center sill having an opening at the end thereof in the bottom wall of said sill for the insertion of a draft gear; outwardly bent flanges on the opposite sides of said opening; a center filler casting extending between the side walls of said sill and secured therein; a bolster having a diaphragm provided with a notch into which the center sill is received; a pair of plates acting as a combination center brace plate, tie plate and bolster bottom flange having their top surfaces welded to the bottom edge of said diaphragm and having their ends adjacent to said sill butt welded to said outwardly bent flanges on said sill and to the sides of said sill opposite to said center filler casting.
30. A railway car underframe comprising a tubular center sill having an opening at the end thereof in the bottom wall of said sill for the insertion of a draft gear; outwardly bent flanges on the opposite sides of said opening; a center filler casting extending between the side walls of said sill and secured therein; a bolster having a diaphragm provided with a notch into which the center sill is received; a pair of plates acting as a combination center brace plate, tie plate and bolster bottom flange having their top surfaces welded to the bottom edge of said diaphragm and having their ends adjacent to said sill butt welded to said outwardly bent flanges on said sill and to the sides of said sill opposite to said center filler casting.
35. A railway car underframe comprising a tubular center sill having an opening at the end thereof in the bottom wall of said sill for the insertion of a draft gear; outwardly bent flanges on the opposite sides of said opening; a center filler casting extending between the side walls of said sill and secured therein; a bolster having a diaphragm provided with a notch into which the center sill is received; a pair of plates acting as a combination center brace plate, tie plate and bolster bottom flange having their top surfaces welded to the bottom edge of said diaphragm and having their ends adjacent to said sill butt welded to said outwardly bent flanges on said sill and to the sides of said sill opposite to said center filler casting.
40. A railway car underframe comprising a tubular center sill having an opening at the end thereof in the bottom wall of said sill for the insertion of a draft gear; outwardly bent flanges on the opposite sides of said opening; a center filler casting extending between the side walls of said sill and secured therein; a bolster having a diaphragm provided with a notch into which the center sill is received; a pair of plates acting as a combination center brace plate, tie plate and bolster bottom flange having their top surfaces welded to the bottom edge of said diaphragm and having their ends adjacent to said sill butt welded to said outwardly bent flanges on said sill and to the sides of said sill opposite to said center filler casting.
45. A process of making a center sill which comprises: providing a tubular structure of curvi-form cross-section; deforming said structure substantial distances inwardly from its opposite ends to provide end portions of polygonal cross-section; cutting portions of the bottom walls of said end portions longitudinally and transversely; and bending outwardly the partially severed parts of the bottom walls to provide integral exterior flanges along the outer sides of said end sections.
50. A center sill comprising a metal tube of curvi-form cross-section deformed at each end to provide end portions of polygonal cross-section.
55. A center sill comprising a metal tube of curvi-form cross-section, and a metal tube of polygonal cross-section integral with one end of said tube of curvi-form cross-section.
60. A center sill comprising a metal tube of curvi-form cross-section, and a metal tube of polygonal cross-section integral with one end of said tube of curvi-form cross-section.
65. A center sill comprising a metal tube of curvi-form cross-section; a metal tube of polygonal cross-section integrally secured at each end of said tube of curvi-form cross-section, each tube of polygonal cross-section being provided with openings; and cheek plates inserted in said openings and butt welded to the edges of said openings.
